(57) **CLAIM**

I claim the ornamental design for a rope cinch, as shown and described.

DESCRIPTION

FIG. 1 is a perspective view of a rope cinch showing the new design;

FIG. 2 is a front elevation view thereof;

FIG. 3 is a rear elevation view thereof;

FIG. 4 is a side elevation view thereof, the opposite side being a mirror image;

FIG. 5 is a top plan view thereof;

FIG. 6 is a bottom plan view thereof; and,

FIG. 7 is a perspective sectional view taken along line 7—7 in FIG. 1.
